(57) **CLAIM**

The ornamental design for an athletic equipment identification band, as shown and described.

DESCRIPTION

FIG. 1 is a front perspective view of the athletic equipment identification band showing our new design;

FIG. 2 is a top plan view thereof;

FIG. 3 is a bottom plan view thereof;

FIG. 4 is a left-side elevation view thereof;

FIG. 5 is a right-side elevation thereof;

FIG. 6 is a front elevation view thereof; and,

FIG. 7 is a rear elevation view thereof.

The dashed lines in the drawings illustrate stitching that forms no part of the claim.

The inverted U-shaped stippling shows the appearance of a pile fabric fastener material.

The J and inverted J-shaped stippling shows the appearance of a hooked fabric fastener material.
